CLAIM

The ornamental design for a magnetic fastener as shown and described.

DESCRIPTION

FIG. 1 is a top view of the top fastener part of the fastener; FIG. 2 is a bottom view of the top fastener part thereof; FIG. 3 is an exploded elevational view thereof, the reverse being a mirror image; FIG. 4 is a bottom view of the lower fastener part thereof; FIG. 5 is a top view of the lower fastener part thereof; FIG. 6 is an exploded bottom perspective view thereof; FIG. 7 is an exploded top perspective view thereof;

FIG. 8 is a bottom perspective view thereof;
FIG. 9 is a top perspective view thereof;
FIG. 10 is a top view of the top fastener part of the fastener showing a second embodiment of my invention;
FIG. 11 is a bottom view of the top fastener part thereof;
FIG. 12 is an exploded elevational view thereof, the reverse being a mirror image;
FIG. 13 is a bottom view of the lower fastener part thereof;
FIG. 14 is a top view of the lower fastener part thereof;
FIG. 15 is an exploded bottom perspective view thereof;
FIG. 16 is an exploded top perspective view thereof;
FIG. 17 is a bottom perspective view thereof;
FIG. 18 is a top perspective view thereof;
FIG. 19 is a top view of the top fastener part of the fastener showing a third embodiment of my invention;
FIG. 20 is a bottom view of the top fastener part thereof;
FIG. 21 is an exploded elevational view thereof, the reverse being a mirror image;
FIG. 22 is a bottom view of the lower fastener part thereof;
FIG. 23 is a top view of the lower fastener part thereof;
FIG. 24 is an exploded bottom perspective view thereof;
FIG. 25 is an exploded top perspective view thereof;
FIG. 26 is a bottom perspective view thereof; and,
FIG. 27 is a top perspective view thereof.
